[57] CLAIM

The ornamental design for a hip abducting seat, as shown and described.

DESCRIPTION

FIG. 1 is a front perspective view of a hip abducting seat showing my new design;

FIG. 2 is a side elevational, cross-sectional view thereof, taken along line II—II of FIG. 3;

FIG. 3 is a top plan view thereof;

FIG. 4 is a front elevational view thereof;

FIG. 5 is a side elevational view thereof, the opposite side elevational view being identical; and,

FIG. 6 is a rear elevational view thereof.
